UNITED STATES PATENT OFFICE.

WILLIAM E. PETTY, OF STORM LAKE, IOWA, ASSIGNOR TO JENS PETER CHRISTIENSEN,
OF NEWELL, IOWA.

COLLAPSIBLE HOG CRATE.

1,426,315.

Specification of Letters Patent. Patented Aug. 15, 1922.

Application filed August 25, 1920. Serial No. 405,791.

To all whom it may concern:

Be it known that I, WILLIAM E. PETTY, a citizen of the United States of America, and resident of Storm Lake, Buena Vista County, Iowa, have invented a new and useful Collapsible Hog Crate, of which the following is a specification.

The object of this invention is to provide an improved construction for a crate 10 adapted to contain a hog, or other animal of similar size, which crate also is adapted to be collapsed or folded for storage and transportation when not in use.

A further object of this invention is to 15 provide an improved construction for a collapsible crate having means for including the ends thereof loosely between the sides thereof when said crate is collapsed or folded.

20 A further object of this invention is to provide improved means for clamping opposite sides of a crate on end portions thereof.

25 A further object of this invention is to provide an improved slide-seat in a side portion of a crate adapted to receive and contact with an end portion or gate.

30 My invention consists in the construction, arrangement and combination of elements 35 hereinafter set forth, pointed out in the claims and illustrated by the accompanying drawing, in which—

Figure 1 is a plan and Figure 2 a side elevation of the improved crate assembled 35 for use. Figure 3 is a cross-section on the indicated line 3—3 of Figure 1, certain portions being further broken away to reveal interior construction. Figure 4 is a horizontal section on the indicated line 4—4 of 40 Figure 2. Figure 5 is an end view and Figure 6 a plan of the crate in collapsed or folded condition.

In the construction of the device as shown 45 the numeral 10 designates a floor, which is provided with spaced cross-bars or cleats 11, 12 on its lower face. Notches 13, 14 are formed in one side margin of the floor 10 and the adjacent ends of the cleats 11, 12 are shortened to the extent of the depth 50 of said notches. Notches 15, 16 are formed in the opposite margin of the floor 10 and the adjacent end portions of the cleats 11, 12 overlap and register with said notches to the margin of the floor. A side member is 55 constructed with slats 17, 18, 19 arranged parallel and spaced apart and connected by

crossbars or cleats 20, 21 on their inner faces and also spaced apart identical with the spacing of the cleats 11, 12. Lower end portions of the cleats 20, 21 are adapted to 60 enter the notches 13, 14 in the floor and extend across adjacent end portions of the cleats 11, 12; the slat 19 being adapted to contact with and extend laterally across the adjacent side margin of the floor and form 65 a box-angle therewith. Adjacent end portions of the cleats 11—20 and 12—21 are connected by hinges, a pair of the hinges being employed. Each hinge is constructed 70 of counterpart straps 22, 22 mounted on opposite marginal faces of the cleat 11 or 12, secured to said cleat by bolts 23, 23, extending across the notches 13, 14 and offset slightly away from the planes of said faces, and straps 24, 24 of like construction 75 and form mounted on opposite marginal faces of the cleat 20 or 21, secured to said cleat by bolts 25, 25, extending partially across the notches 13, 14 between the offset portions of the straps 22, 22, a hinge-pin or bolt 26 pivotally connecting the overlapping portions of the straps and extending 80 across the cleat 20 or 21, the straps 24, 24 being off-set at 27 an amount substantially equal to the thickness of the floor 85 10 to permit the side member and bottom member to be extended substantially in the same plane (Fig. 5). The shape of the hinge straps 22, and the overlapping of the cleats 20, 21 on the floor 10 and cleats 11, 12, 90 permits movement of the bottom member and side member relative to each other in one direction to form a right angle but not to form an acute angle, whereby the side member may be arranged in a plane perpendicular to the plane of the bottom member 95 (Fig. 3), in which position the bottom braces against the cleats 20, 21 and lends stability 100 to the frame. U-shaped metal loops 28, 29 are mounted in embracing relation on, and the closed central portions thereof extend beyond the upper ends of the cleats 20, 21, and said loops are secured to the sides of the cleats by screws 30. Another side member is constructed with slats 31, 32, 33 arranged 105 parallel and spaced apart and connected by cross-bars or cleats 34, 35 on their inner faces also spaced apart identical with the spacing of the cleats 11, 12, 20 and 21. Lower end portions of the cleats 34, 35 are 110 adapted to enter the notches 15, 16 in the floor 10 and abut, at times, the upper faces

of end portions of the cleats 11, 12; the slat 33 being adapted to contact with and extend laterally across the adjacent side margin of the floor and form a box-angle therewith. Strap-hinges 36, 37 are mounted on the inner faces of the cleats 34, 35, respectively, are spaced from the lower ends of said cleats an amount substantially equal to the thickness of the floor 10, and are secured to the upper surface of the floor (Figs. 3 and 4). The location of the hinges 36, 37 and the abutting relations of the cleats, permits a movement of the side and bottom members relative to each other in one direction only from a right angle so that said members may be folded one on the other (Fig. 5) or extended with the side member in a plane perpendicular to that of the bottom member (Fig. 3) and in the latter position said arrangement lends stability to the frame.

A cover member is constructed with slats 38, 39 arranged parallel and spaced apart and also spaced from the side members and 25 materially less length than the floor 10 and slats of the side members, and cleats 40, 41 on their inner faces, which cleats are of a length substantially corresponding with the width of the floor and extend, at times, across 30 the upper ends of the cleats 20, 21 and 34, 35. One end portion of the cleats 40, 41 is rounded on the lower side and is secured by hinges to the upper ends of the cleats 34, 35. These hinges are constructed with 35 straps 42, 42 lying on opposite sides of the upper end portion of each cleat 34, 35 and secured thereto by screws 43 and overlapping the cleats 40, 41, and straps 44, 44, lying on opposite sides of the adjacent end portions 40 of the cleats 40, 41, secured thereto by screws 45, off-set and overlapping the upper ends of the straps 42, 42 and pivoted thereto by hinge-pins or bolts 46 extending through the overlapping portions of the straps and the 45 adjacent cleat-end. The overlapping arrangement of the cleats 34, 35, 40 and 41 and the arrangement of the hinges connecting them, permits the cover member to be moved through an arc of substantially ninety degrees only. Thus is provision made for arranging the cover member in a plane perpendicular to the plane of the second side member, in which position it lends stability to the frame, or, for extending said members in substantially the same plane (Fig. 5) 50 when the crate is folded or collapsed for storage or unused transportation. The end portions of the cleats 40, 41 are adapted to extend through the loops 28, 29 to an extent permitted by contact of said loops with one side margin of the slat 39 and latches 47, 48, of leaf-spring type, are mounted in grooves 49 formed in the cleats beneath the central portions of said loops. 55 The latches 49 are formed with notches 50

in their upper faces adapted to receive and engage the central portions of the loops 28, 29 and prevent accidental withdrawal of the cleats 40, 41 from said loops. The slat 39 also is formed with transverse slots 51 opening through its lower face and adapted to receive the upper portion of each latch 47, or 48 at times and permit a range of movement thereof. The detachable connection of the cover member to the first side member, 75 through the interengagement of the cleats, loops and latches lends stability to the frame and prevents accidental movement of either or any member thereof relative to another. Pairs of cleats 52, 52—53, 53—54, 54—55, 55 80 are fixed to and extend across the inner faces of end portions of the side members of the crate, being fixed to the slats of said side members, and the units of each pair are spaced apart a distance substantially equal 85 to the thickness of any slat employed. End gates are employed to close the ends of the crate and each is constructed with slats 56, 57, 58 arranged parallel and spaced apart and cleats 59, 60 extending across the inner 90 faces of and connecting said slats, said cleats also being arranged parallel and spaced apart.

The end-gates are mounted on and perpendicular to end portions of the floor 10, 95 the slats of the end-gates abutting the slats of the side members within the pairs of cleats 52, 53, 54, 55, which cleats prevent movement of the end-gates longitudinally 100 of the side members. Metal wear-plates 61 are mounted on the slats of the side members of the crate and are overlaid at their margins by the cleats 52, 53, 54, 55, and said plates take the wear and strain of engagement with ends of the slats of the end-gates. 105 Tie-members are employed to connect end portions of the side members of the crate across the end-gates and each is constructed as follows: An eye-bolt 62 is mounted through registering holes in the outermost 110 cleat 52 or 53 and the slat 32 and a link 63, formed with eyes 64, 65 having their axes at right angles to each other, is pivoted by means of its eye 64 to the eye of the bolt. An eye-bolt 66, provided with a handle nut 115 67, is mounted through registering holes in the outermost cleat 54 or 55 and the slat 18 and a bar 68, formed with a hook 69 and eye 70 on its ends arranged at right angles with each other, is pivoted by means of its eye 70 to the eye of said bolt 66. The side members of the crate may be connected by engaging the hooks 69 in the eye 65 and may be drawn tightly to end portions of the 120 end-gates by strain applied to the tie-members through the handle nuts 67 to prevent accidental removal of the end-gates; and said strain may be relaxed by a reverse movement of the handle-nuts to permit 125 manual removal of either end-gate. The tie- 130

members may be disconnected by releasing the hooks 69 from the eye 65, to permit collapsing or folding of the crate. Either end-gate may be removed to permit an animal to 5 enter or leave the crate without disturbing the other end-gate or the loop and latch connections. The cleats 11, 12, 20, 21, 34, 35, 40 and 41 are of a thickness substantially double that of the floor 10 and the slats of 10 the end-gates. An angle-bar or slide seat 71 is mounted on each of the cleats 20, 21, 34 and 35 in such manner as to provide a rack or container, in conjunction with the slats of the side members, adapted to receive and 15 retain the end-gates (see dotted lines in Fig. 1) when said end-gates are removed preparatory to collapsing or folding the crate. The end-gates may be placed or removed 20 slidingly relative to the slide-seats 71 also when the other members are in folded position. Screw-hooks 72, two for each end of 25 the crate, are mounted on the cleats 20 and 21 (Fig. 5) and are adapted to engage at times with eyes 73, in like number, mounted in the cleats 34, 35, 40 and 41. The screw 30 eyes 73 and hooks 72 are provided to connect the members in folded or collapsed condition and, when said members are so arranged and the end-gates are located in the 35 slide-ways provided, said end-gates are held as in a clamp and the slats thereof are parallel with the slats of the side members and mismatched or staggered relative thereto. When the hooks 72 are released from the 40 eyes 73, the end-gates may be slid to and fro into or out of the slide-seats 71 as desired. The crate may be moved and carried about in folded or collapsed condition by using the loops 28, 29 as handles.

45 When the crate is set up and connected for use, it presents a rigid, strong and well-ventilated container with a solid floor forming closed angles with the sides and ends to prevent projection of legs or feet through the bottom, well adapted for retention and transportation of one or more hogs, or similar animals. When the crate is folded or collapsed it occupies materially less cubic space than when set up and hence is adapted 50 for convenient and economical return transport, handling and storage, thus providing for repeated use of a given crate with much saving in cost of material and labor.

I claim as my invention—

55 1. A collapsible crate having a solid bottom member, slatted side members hinged to the bottom member and adapted to form box-angles therewith, a cover member of less length than the bottom and side members hinged to one side member and slidingly 60 engaging the other side member, jointed tie-rods parallel with each other connecting the side members and end-gates removably and replaceably and slidingly mounted between the side members and also in a plane

between that of the tie-rods and that of the ends of the cover member and adapted to form box-angles with the bottom member.

2. A collapsible crate having a bottom member formed with notches in its side 70 margins, side members hinged to the bottom members and having cleats adapted to extend within said notches, a top member hinged to one side member and having sliding engagement with the other side 75 member, the side members being formed with opposing slide-ways, end-gates slidingly mounted in said ways, and tie-members connecting said side members and adapted to clamp them to the end-gates. 80

3. A collapsible crate having a bottom member formed with notches in its side margins and cleats extending to the notches at one end and across the notches at the other end, a side member hinged to said bottom 85 member and having cleats extending in some of said notches and across the adjacent ends of the bottom cleats, another side member hinged to the bottom member and having cleats extending through the remaining 90 notches and abutting the projecting end portions of the bottom cleats, said side members being parallel with each other, a cover member hinged to one side member and slidingly engaging the other side member, and 95 end-gates detachably mounted between said side members.

4. A collapsible crate, having a bottom member, side members hinged to the bottom member and a cover member hinged to 100 one side member, said hinge connections adapting the crate to be folded with the bottom member and one side member in one plane and the cover member and other side member in another plane substantially parallel with the first plane, means for detachably connecting said members when so folded, and end-gates separate from and adapted to be mounted slidably between and parallel with said side members when in folded 105 positions.

5. A collapsible crate, having a bottom member, side members hinged thereto, a pair of loops on one side member, a cover member hinged to the other side member and having cleats adapted to be embraced by said loops, jointed adjustable tie-rods parallel with each other connecting said side members across the space between them, and end-gates adapted to be mounted between 115 and at right angles to said side members.

6. A collapsible crate, having a bottom member, side members hinged thereto, a pair of loops on one side member, a cover member hinged to the other side member and having cleats adapted to be embraced by said loops, latches connecting said cleats and loops, and end-gates adapted to be mounted between said side members. 125

7. A collapsible crate, having a bottom 130

member, side members hinged thereto, a cover member hinged to one side member and adapted to be connected with the other side member, said side members being 5 formed with slide-ways, the cover member being of less length than and centrally located between the ends of the side members, and end-gates adapted to be mounted in said slide-ways and extending between the side 10 members and also adapted to be moved across the plane and outside the ends of the cover member when said cover member is in closed position.

8. A collapsible crate, having side members suitably connected and formed with 15 slide-ways, wear plates mounted thereon and forming the bottoms of the slide-ways, end-

gates adapted to be mounted between said side members and abutting said wear-plates, and tie-rods connecting said side-members 20 and adapted to clamp the wear-plates to said end-gates.

9. In a collapsible crate having side members and end-gates extending between them, the combination therewith of eye-bolts in 25 the side members, a link pivoted to one bolt and a hook-bar pivoted to the other bolt and adapted to engage the link, said link and hook-bar extending parallel with the end-gate and spaced therefrom. 30

Signed at Des Moines, in the county of Polk and State of Iowa, this 8th day of July, 1920.

WILLIAM E. PETTY.
